UNITED STATES PATENT OFFICE.

THOMAS WHEATLEY, OF SYRACUSE, NEW YORK.

DESIGN FOR A DEFLECTOR FOR VALVES.

SPECIFICATION forming part of Design No. 33,556, dated November 13, 1900.

Application filed October 15, 1900. Serial No. 33,169. Term of patent 7 years.

To all whom it may concern:

Be it known that I, THOMAS WHEATLEY, of Syracuse, in the county of Onondaga, in the State of New York, have invented and produced a new and original Design for Deflectors for Valves, of which the following, taken in connection with the accompanying drawings, is a full, clear, and exact description.

Figure I is an isometric view of my new design of deflector. Fig. II is a top plan. Fig. III is a side elevation.

As shown in the drawings, the leading or material features of my design are a circular flat top 1, with a central perforation 2, an annular base 3, arranged parallel to the top and

of larger diameter, and short outwardly-inclined bars 4, connecting the base to the top and leaving between them elongated openings 5.

Having described my invention, what I claim as new, and desire to secure by Letters Patent, is—

The design for a deflector, as herein shown and described.

In testimony whereof I have hereunto signed my name.

THOMAS WHEATLEY.
